UNITED STATES PATENT OFFICE

DUNCAN KENNER, OF NEW ORLEANS, LOUISIANA, BY COURT ORDER MRS. EMMA TUJAGUE KENNER SOLE HEIR AND LEGATEE OF DUNCAN KENNER, DECEASED

MOP WRINGER AND HOLDER

Application filed May 28, 1929. Serial No. 366,640.

This invention relates to a combined mop wringer and holder.

The principal object of the invention is the provision of a mop wringer and holder which embodies improved features of construction to the end that it will be positive in operation; that it will be adapted for the purpose of wringing any ordinary mop pad made of numerous thrums, strands of yarn or cords, and pads made of any fibrous material; that will permit the user to fold the mop pad and put a holding pressure thereon for carrying out scrubbing or mopping operations; and that enables a mop pad to be quickly inserted and removed whenever necessary or desirable, and which enables the user to change from one kind of mop pad, such as a water mop pad, to an oil mop pad, or a long slosh-mop pad to a small mop pad to be used in restricted places.

The nature of the invention and its distinguishing features and advantages will appear when the following specification is read in connection with the accompanying drawing, in which—

Figure 1 is a front view of a mop wringer and holder constructed in accordance with the invention, the mop pad being shown in dot and dash lines.

Fig. 2 is a sectional view taken substantially on the line 2—2 of Fig. 1 and looking in the direction indicated by the arrows.

Fig. 3 is a side view showing the relationship of certain parts for carrying out mopping or wringing operations.

Fig. 4 is a view similar to Fig. 3, but showing one of the levers actively engaged for changing the position of one of the wringing rollers to enable the insertion and removal of a mop pad between the wringing rollers.

Fig. 5 is a detail view of the crank handle for rotating one of the wringing rollers.

Referring now more particularly to the several views of the drawing, it will be apparent, that the mop wringer and holder includes a frame or yoke 10 consisting of two substantially similar yoke members 11 and 12 of metal rod material, together with a socket or ferrule 13 which receives one end of a handle 14. The yoke members 11 and

12 are tightly held together by metal clips 15. The yoke member 11 has terminal eyes 16 which constitute bearings for the opposite ends of a shaft 17 of a wringing roller 18. The roller 18 is made of wood, but may be made of any other suitable material, and is fluted as indicated at 19. The yoke member 12 is provided with terminal eyes 20 which constitutes bearings for the opposite ends of a shaft 21 of a wringing roller 22 equal in length to the length of the roller 18. The roller 22 has circular flanges 23 spaced axially of the roller 22 for a purpose explained hereinafter. Side guard plates 24 of metal are supported by the opposite ends of the shaft 17, the plates being provided with holes for that purpose. The opposite ends of the shaft 21 extend respectively through slots 25 in the plates 24. The plates 24 are similar in size and shape, and are disposed between the ends of the rollers 18 and 22 and the adjacent portions of the frame or yoke 10. End walls of the slots 25, into engagement with which the opposite ends of the shaft 21 are moved, serve with the shaft ends to hold the roller 22 spaced from the roller 18 a suitable distance to properly accommodate a mop pad 26 indicated in dot and dash lines.

In accordance with one of the features of the invention, the yoke members 11 and 12, by reason of the manner in which they are connected together, and the inherent springiness thereof, have pressure provision for constantly urging the roller 22 toward the roller 18. Consequently the mop pad will at all times be effectively gripped for carrying out mopping operations, and also for carrying out wringing operations.

In accordance with another feature of the invention use is made of lever means for effecting the movement of the roller 22 away from the roller 18 to enable the ready insertion of a mop pad between said rollers, and also for removing the same from between said rollers. Said lever means comprises similar levers 27 having the opposite ends of the shaft 21 as their fulcrums. Each lever 27 carries a spring 28, the free end of which is engageable with the related eye 20 of the yoke

member 12 to hold the lever 27 in an inactive position, as shown in Fig. 3. The levers 27 may be swung to the position shown in Fig. 4, in which the ends 29 thereof bear against portions of the yoke member 11 with a camming effect, causing the yoke member 12 to be sprung away from the yoke member 11, thus changing the position of the roller 22 with respect to the roller 18. It will then be possible to readily insert a mop pad between the rollers 18 and 22, and also make it possible to readily remove the same from between the rollers. The levers 27 may be swung in a reverse direction, whereupon the yoke member 12 will spring back, bringing the roller 22 to its original position.

In order to effect the rotation of the roller 18, there is provided a gear 30 fast on one end of the shaft 17, which meshes with a pinion 31 fast on one end of a crank 32 mounted for operation on one of the plates 24 and supported in part by a bearing member 33 secured to said plate. The crank 32 has a handle 34, which may be swung to different positions and which is held in these positions by the employment of a pin 35 on the crank arm 36, engageable in notches 37 in the handle end 38 which loosely surrounds the arm 36, there being a spring 39 on said arm held in place by a pin 40 carried by the arm, which spring, bears against the end 38 to releasably hold the handle 34 in the said positions.

The opposite ends of the shafts 17 and 21 have arranged thereon suitable retaining means such as nuts or washers 41 held in place by pins or heads formed on the ends of the shafts. This provision serves to hold the yoke 10, plates 24 and levers 27 in position, or in the proper assembled relationship.

In accordance with another feature of the invention there are provided scraper elements 42 and longitudinal guard plates 43 supported at the opposite ends by the plates 24. The scraper elements 42 extend parallel to and adjacent said rollers 18 and 22. The scraper elements 42 constitute a means to remove foreign matter from the mop pad during the remaining operation, and also to remove the loose ends of the material constituting the mop pad, which would adhere to the rollers when wet, and would wind around said rollers and impede rotation of said rollers. With the handle held in an ordinary mopping position and the mop pad disposed forwardly it is evident that the front longitudinal guard plate 43 will rest upon the mop pad keeping all parts of the wringer the thickness of the mop pad from the floor. In the operation of mopping the mop pad is also used backwardly or under the wringer; in this position the back longitudinal guard plate 43 rests upon the mop pad keeping all parts of the wringer the thickness of the mop pad from the floor.

Attention is now called to the fact that the flanges 23 of the roller 22 prevent the mop

pad from spreading out sidewise against the plates 24, which if permitted, would cause undue friction and require unusual effort in wringing the mop pad. Furthermore the sides of the mop pad will not be subjected to unusual wear, and will be caused to move straight when subjected to the action of the rollers 18 and 22.

It will also be apparent that the guard plates 24 prevent the mop pad from being forced between the frame or yoke members 11 and 12 and the ends of the rollers, when the mop pad is subjected to the action of said rollers in the wringing operation. The side plates may be beveled so as to offer as little resistance as possible.

It will also be apparent that by the provision of the gear 30 and pinion 31 together with the crank handle, the user is enabled to carry out wringing operations in a convenient manner. The gear and pinion perform the function of turning roller 18 in response to the turning of the crank in a right hand manner, to apply traction to the underside of the mop pad, thereby causing the mop pad to curve away from the rollers, so that the water squeezed from the mop pad cannot fall back upon the wrung portion thereof, and also for operating the roller 18 to draw the mop pad into the desired association with the rollers. Furthermore by providing the adjustable handle 34, it is possible to move the same to an out of the way position in which it will be retained against unintentional movement.

I claim:

1. A mop wringer and holder comprising the combination of yoke members having a handle, cooperable wringing rollers mounted for rotation on said yoke members respectively, side guard plates, means carried by the yoke members which support said guard plates respectively adjacent the ends of said rollers, the edge of each guard plate projecting beyond the peripheral surfaces of both rollers, and scrapers carried by said guard plates, said scrapers extending parallel to and adjacent said rollers to receive therebetween a mop pad to remove foreign matter therefrom during the wringing operation.

2. A mop wringer and holder having the combination of resilient yoke members connected together so that they are urged towards each other, a handle connected with said yoke members, wringing rollers mounted on said yoke members respectively, said yoke members affording pressure provision for constantly urging one of said rollers toward the other roller, and means operable in conjunction with said yoke members to change the position of one roller with respect to the other roller, for the purpose of inserting a mop pad between said rollers or for removing the mop pad from between the rollers.

3. A mop wringer and holder having the

combination of resilient yoke members connected together so that they are urged towards each other, a handle connected with said yoke members, wringing rollers mounted on said yoke members respectively, said yoke members affording pressure provision for constantly urging one of said rollers toward the other roller, scraper elements, and means positioned on the roller shafts supporting said scraper elements disposed in spaced relation adjacent said rollers, to receive therebetween a mop pad to remove foreign matter therefrom during the wringing operation.
